CLAIM

The ornamental design of a hitch pin, as shown and described.

DESCRIPTION

FIG. 1 is a side view of a hitch pin showing my new design;
FIG. 2 is a second side view thereof;
FIG. 3 is a perspective side view thereof; and,
FIG. 4 is an end side view thereof.

The broken lines in the figures are included for the purpose of illustrating portions of the hitch pin and form no part of the claimed design.
